A. J. NICHOLAS

WELL PUMP

Filed March 7, 1924

INVENTOR:

Andrew J. Nicholas

BY

Allen & Allen

ATTORNEYS.

UNITED STATES PATENT OFFICE.

ANDREW J. NICHOLAS, OF PHILADELPHIA, PENNSYLVANIA, ASSIGNOR TO A. D. COOK,
INC., OF LAWRENCEBURG, INDIANA, A CORPORATION OF INDIANA.

WELL PUMP.

Application filed March 7, 1924. Serial No. 697,864.

To all whom it may concern:

Be it known that I, ANDREW J. NICHOLAS, a citizen of the United States, and a resident of Philadelphia, in the county of 5 Philadelphia and State of Pennsylvania, have invented certain new and useful Improvements in Well Pumps, of which the following is a full, clear, and exact description, reference being had to the accompanying drawing, forming part of this specification.

My invention relates to pumps, particularly those using double plungers, and to the provision of means for measuring the 15 depth of water within the well casing, where it is impossible to get a water level finder down between the inside of the well casing and the outside of the pump pipe connections.

20 In double plunger pumps, there is normally a cylinder in the pump pipe, which is lowered inside the well casing, through which water is drawn, and the plungers working in opposite directions serve to draw 25 the water from the well, and force it up through the pipe to the point of delivery.

In such pumps, heretofore, so far as I am advised, there has been no way of measuring the depth of liquid in the well without 30 pulling out the plungers and sounding with a bob and line.

It is the object of my invention to provide for hollow pump rods, to the end that means is provided for measuring the depth 35 of the liquid, be it water or oil, within the well casing, without removing the plungers.

I accomplish my object by that certain construction and arrangement of parts to be hereinafter more specifically pointed out 40 and claimed.

In the drawing:

Figure 1 is a side elevation of the plunger system of a deep well pump.

Figure 2 is a longitudinal section through 45 the device of Figure 1.

Figure 3 is a sectional view on a larger scale of the preferred sounding device, in which provision is made for determining well depth without regard to a slack line, 50 as is the usual mode of sounding.

I have shown merely one of the standard double plunger pump and rod systems in use for deep well pumps by A. D. Cook,

Inc., at Lawrenceburg, Indiana, and do not intend to limit the application of my invention to this form of pump alone.

I show the lower plunger 1 having the hollow pump rod 2, extending up to a point of application of power. I show also an upper plunger 3, having, as is usual, a hollow rod or pipe 4, extending up around the first rod 2, to a point of application of power. It will be understood that these plungers will operate in a deep well cylinder, normally at the bottom of the pump pipe.

The plunger 2 being hollow, and extending to the lower extremity of the pumping system, is used by me for lowering a device into the well, which device tells depth 70 by other means than merely slackness of the line to which the weight or bob is attached. I can also use the hollow plunger itself to determine the water depth by means of variations in air pressure applied to the 75 top of the plunger.

The device used by me, by preference as being more readily operated and read by rule of thumb, is a hose 5, of a diameter to slip down through the plunger rod, at the 80 end of which hose is a weighted rod 6. The rod 6 is of substantially the diameter of the hose, and has a hollow bore 7, terminating in a lateral port 8, the bore communicating with the interior of the hose.

To determine the depth of water in the well, the hose is fed down through the hollow pump rod so that the weight will carry the end out through the bottom of the plunger. Then by forcing air into the hose and noting the point when the hole or port 8 becomes submerged in liquid, by the variation in air pressure in the air line, the operator can tell when the port has come just below the level of the liquid in the well or casing. He then stops feeding down the hose and withdraws and measures it. Knowing the length of the hose, he can thus tell the liquid level in the well bottom, which is the factor he wishes to determine.

Having thus described my invention, what I claim as new and desire to secure by Letters Patent, is:—

1. A well pump having a plunger, and a plunger rod, said rod being hollow and opening into the bottom of the well, and

means operating through said hollow rod for determining the depth of liquid in the well.

2. A well pump having a plunger, and a
5 plunger rod, said rod being hollow and
opening into the bottom of the well, and
means operating through said hollow rod
for determining the depth of liquid in the
well, said means comprising a member to
10 be lowered through the hollow rod, and
means in said member for indicating the
point when it becomes submerged in liquid.

3. A well pump having a plunger, and a

plunger rod, said rod being hollow and
opening into the bottom of the well, and
means operating through said hollow rod
for determining the depth of liquid in the
well, said means comprising a tubular ele-
15 ment adapted to be lowered through the
hollow rod and a port in the lower end of
said element, whereby the change in pres-
sure of a column of air forced through the
tubular element will indicate the instant of
20 submergence of the said port.

ANDREW J. NICHOLAS.
